US00D910545S

(12) **United States Design Patent** (10) Patent No.: **US D910,545 S**
Dinh et al. (45) Date of Patent: **** Feb. 16, 2021**

(54) **BATTERY FOR AN ELECTRONIC DEVICE**

(71) Applicant: **Apple Inc.**, Cupertino, CA (US)

(72) Inventors: **Richard Hung Minh Dinh**, San Jose, CA (US); **Sherry Lee**, Oakland, CA (US); **Shayan Malek**, San Jose, CA (US); **Kurtis James Mundell**, San Francisco, CA (US); **Benjamin J. Pope**, Sunnyvale, CA (US)

(73) Assignee: **Apple Inc.**, Cupertino, CA (US)

(**) Term: **15 Years**

(21) Appl. No.: **29/660,999**

(22) Filed: **Aug. 23, 2018**

(51) LOC (13) Cl. **13-02**

(52) U.S. Cl.

USPC **D13/103**

(57)

CLAIM

The ornamental design for a battery for an electronic device, as shown and described.

DESCRIPTION

FIG. 1 is a bottom front perspective view of a battery for an electronic device showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the battery for an electronic device that form no part of the claimed design.

1 Claim, 6 Drawing Sheets
